Primary Examiner — S. Bryan Reinholdt, Jr.

(74) Attorney, Agent, or Firm — Sandy Lipkin

(57)

CLAIM

The ornamental design for the skateboard leash, as shown and described.

DESCRIPTION

FIG. 1 is a top perspective view of the skateboard leash of the instant invention.

FIG. 2 is a bottom perspective view thereof.

FIG. 3 is a bottom view thereof.

FIG. 4 is a left side view thereof.

FIG. 5 is a right side view thereof.

FIG. 6 is a front view thereof.

FIG. 7 is a top view thereof; and,

FIG. 8 is a bottom view thereof.

1 Claim, 5 Drawing Sheets
